(57) **CLAIM**

The ornamental design for a tire, as shown and described.

DESCRIPTION

FIG. 1 is a perspective view of a tire;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is an enlarged partial front view thereof.

The tread pattern is understood to repeat throughout the circumference and the shoulder of the tire. Broken lines in the drawings are used for demarcation of enlarged portions of the tire and form no part of the claim.
